TEACHING AID FOR MEASURING THE ACCELERATION OF A FALLING BODY

Roger D. Stephenson, Overland Park, Kans., assignor to
Physics Apparatus Research, Inc., Overland Park, Kans.

Filed Aug. 16, 1971, Ser. No. 172,372

Term of patent 14 years

Int. Cl. D19—07

U.S. Cl. D25—1

Fig. 1.

Fig. 2.

Fig. 3.

FIG. 1 is a front elevational view of a teaching aid for measuring the acceleration of a falling body showing my new design with a portion of the elongated stand shown broken away;

FIG. 2 is a right side elevational view thereof;

FIG. 3 is a top plan view thereof;

FIG. 4 is a left side elevational view thereof;

FIG. 5 is a rear elevational view thereof; and

FIG. 6 is a top plan view of another embodiment of my new design wherein the base is round rather than square.

I claim:

The ornamental design for a teaching aid for measuring the acceleration of a falling body, as shown and described.
